BUILDING CONSTRUCTION

Robert L. Davison, New York, N. Y., and George M. Rapp, New Haven, Conn., assignors to John B. Pierce Foundation, New York, N. Y., a corporation of New York

Application October 12, 1943, Serial No. 505,904

8 Claims. (Cl. 108—1)

This invention relates to improvements in structures; and particularly to structural supports for transverse or lateral loadings in the roof structures of buildings.

The trend toward low-cost structures, in which the objectives are economy of space, material, and labor, has been accelerated by present conditions. Wall structures of such buildings have been improved and simplified by the employment of pre-fabricated panels embodying resin-bonded plywood or the like, but almost universally the roof construction follows the conventional forms of built-up trusses, girders, or rafters.

It is an object of this invention to provide a roof support which will combine the high load-carrying efficiency of the truss and arch types with the simplicity of girders or rafters.

It is an object of the invention to provide a roof support which, requiring few pieces, few joints, and a minimum of fabrication, will be suitable for low-cost mass production of houses.

It is an object of the invention to provide an arch roof support of simple construction, having the efficiency of "higher type" structures such as trusses and complex arch types.

It is an object of the invention to provide an arch embodying pre-stressed, relatively thin structural members, either of wood, plywood, or metal.

It is an object of the invention to utilize to the utmost the load-carrying capacities of the materials, while simplifying the structure to reduce the material and labor costs to a minimum.

Our invention comprises the formation of a roof-supporting structure by springing a slender member into pre-determined arch-like shape by the application of forces in opposing directions at the opposite ends of the slender member and maintaining the member in such form by means of a horizontal tie member. By tying together the ends of the arched member, it becomes a self-contained and self-sustained structure and accordingly does not impose any thrust against the top of the supporting walls. A slender beam, if caused to assume such calculated arcuate shape or camber by the application of endwise applied pressure, will have considerable load-carrying strength, as well as resiliency, its load-carrying strength being enhanced by reason of its pre-stressing which is opposite in sign to that of the subsequently applied loads.

A roof arch according to our invention, therefore, comprises a relatively light structural member, highly pre-stressed by the application of endwise oppositely directed forces, held in arch form by a tie member in tension, and combined with resilient sheet material of the nature of plywood which is co-extensively secured to the upper, i. e., convex, face of the bowed or arched resilient slender member, whereby such resilient sheet ma-

terial is also pre-stressed and by reason of its co-extensive securement to the resilient bowed member high load-carrying strength and resistance against deformation incident to wind, snow and other live load conditions, are imparted to the thus formed roof-understructure. Our invention differs from a conventional tied arch in that the curved member is highly stressed in its free or unloaded condition, and by reason of the compression forces brought about within such slender member by the stated pre-stressing, the curved slender member enables the assembled roof structure to withstand "dead" and "live" loads. It will be observed that the "dead" and "live" loads to which the resulting roof structure may be subjected are in directions counter to the pre-stressed forces engendered in the slender, i. e. inherently weak, arched member by the forces applied at the opposite ends of the slender member in opposing directions.

As appears more fully hereinafter, sheet material is secured co-extensively at its underface relative to the outer, i. e., convex, face of the bowed slender member, thereby completing the roof structure and whereby the "dead" and "live" loads to which the roof structure may be subjected are uniformly distributed over the concerned surfaces of the slender bowed member.

In the accompanying drawing:

Fig. 1 is an elevation of an arch roof-support according to the present invention;

Fig. 2 is a plan view of a portion of a roof including two arch supports with layers of the covering or roofing material exposed;

Fig. 3 is a detailed sectional view on line 3—3 of Fig. 2 of a preferred form of maintaining a bowed member in its arched form by means of a tie member and end-thrust blocks;

Fig. 4 is a plan view taken on lines 4—4 of Fig. 3;

Fig. 5 is a central sectional vertical elevation of Fig. 1; and

Fig. 6 is a detail view, in section, of a preferred means of joining a plywood sheathing.

Our improved arch-type roof support 10 comprises essentially an arched member 11, a bottom chord or tie member 12, end-thrust blocks 14, 14 at the respective ends of the tie member and cover plates 15, 15 at said tie member ends overlying the ends of said member 11.

For a typical room span of 24 feet, an arch rise of 2' 3" provides adequate drainage and efficient arch action; and assuming a dead load of 5 pounds per square foot, a live load of 20 pounds per square foot (distributed uniformly on the horizontal projection), and a wind load of 10 pounds per square foot of uplift distributed uniformly over the whole span, high-stress grade lumber such as 1800f or 2000f Douglas fir or yellow pine, 1½ inches thick and 5¾ inches

wide ("finished four sides" dimension) is fully capable of safely sustaining the stresses resulting from the pre-stressing and such loading.

For uniformity, the tie member or bottom chord 12 is made of equal section; the tie member may be of selected "yard" lumber, and not of the high-stress material employed for the arch member 11.

The bottom chord 12 is prepared to receive the arch member 11 by securing to the ends of said chord 12 end-thrust or buffer blocks 14. Standard high-efficiency connectors such as the "Teco" toothed ring connector 16 are employed, the illustrated bolt and washer assembly passing through the block 14, fastener 16 and chord 12, as shown.

The arched member 11 is accurately pre-cut as to length, and its ends beveled as shown at 17 in Fig. 3, so that upon the assumption of the ultimate arcuate form, the end edges of the arched member 11 will be vertical to the chord 12 and parallel to the edges of the blocks 14. Such pre-cut and beveled material, which is at that time in a normal flat condition, is placed horizontally over its companion tie member already having the blocks 14 attached, and while supported at approximately its final position at mid-span by means of a pre-cut center strut 21 standing loosely in position, it is slowly bent downward at both ends (a single man at each end utilizing less than his full weight may do this) until the ends are in their approximate final position and bearing lightly against the pre-inserted double wedges 18-20; as it is held in this position the temporary center strut is kicked out of position, allowing the full thrust of the curved member to come into bearing against these wedges. The wedges next are driven "home," or that is, closed until the desired center rise is attained. The plates 15, 16 are then nailed into place and the arch fabrication is completed.

It is obvious that a slight change in length to the arch member 11 will result in a proportionately much larger change in rise, and therefore the wedges 18, 20 of oak or other hardwood permit of adjustment. As is illustrated in Fig. 4 and indicated in Fig. 3, the wedges 18, 20 are arranged in pairs in face-to-face engagement with their respective tapered, reduced end portions directed in opposite directions, thus facilitating adjustment between the respective ends of each arched member and its associated block 14, and in turn with the associated chord member 12.

The cover plates 15 positively confine the bent arch member 11 and cover the heads of the bolts, see Fig. 3, and combine to accommodate the co-extensively secured sheathing and subsequently applied roofing material, referred to more fully hereinafter.

At suitably spaced intervals across the span of the arch it is preferable, by reason of the light material employed for the chord 12, to insert struts 21, which function to stiffen the tie member against the nailing of the ceiling material to the underside thereof. These struts 21 may be 2 x 4 vertical studs which connect the top and bottom chords.

In construction, a succession of such arches is supported on and secured to the top of the walls 22 of the building, say, on 24 inch centers. Since each arch is a self-contained and self-sustained structure, no lateral thrusts are imposed on the building walls by reason of the stress condition

of the member 11. The 24 inch spacing of arches affords a safe span for a plywood sheathing 23, selected because of its availability in large size sheets, which facilitates the rapid erection of the roof structure. The plywood is preferably co-extensively secured to the arches by nailing and gluing, and thus cooperates with the arches in the carrying of live loads, the application of the plywood sheathing upon the upper, i. e. convex, face of the resilient bowed arch member, causes a pre-stressing of such sheathing, and due to the resiliency of the bowed arch member, combined with the co-extensive securing and resiliency of the bowed sheathing, the resulting roof structure embodies high load-bearing attributes, and under the conditions of wind, snow and other live load, including travel on the roof by a roofer or repairman, deformation of the roof structure is minimized and the imposed forces incident to such live load condition are distributed over the surrounding portions of the roof structure. In normal times plywood, of $\frac{3}{8}$ inch or $\frac{1}{2}$ inch thickness is readily obtainable from stock in 12 feet long pieces; under present war-time conditions 8 feet lengths can be employed, when the longitudinal joints of the plywood are made with ship-lap connections with "speed-nut" fasteners such as are employed in aircraft plywood work. A typical joint is shown in Fig. 6 in which the "speed-nut" connections are designated 25.

The weather surface 24 of the roof is advantageously standard roll sheet roofing applied according to standard practices.

In calculating the stresses induced in the arch member 11 by the application of endwise pressure sufficient to obtain enough center rise to assure good drainage and efficient arch action, certain basic assumptions of allowable unit stresses have been established.

The pre-stress bending has been established as 2800 pounds per square inch; although this stress is approximately 50% greater than the 1800 pounds basic stress of 1800f Douglas fir, it is considered safe because of the transitory character of this loading.

Dead load causes a reduction in this stress, because the stress introduced by the dead load is of opposite sign than the pre-stress. The combination of dead load and pre-stress has been set at 1800 pounds per square inch in the preliminary calculations.

For the combination of pre-stress, dead load, live load, and wind, a figure of 2800 p. s. i has been set, the higher value being justified on the basis of the severity of the combination, the transitory nature of the live load, and the utilization of the plywood sheathing as part of the stress-carrying section.

For a twenty-four foot span and an arch of 2' 3" rise, and the combination of loading and materials above set out, the maximum stresses on the arch member 11 under full-span loading are +1640 p. s. i. (top fiber) -1220 p. s. i. (bottom fiber) and -470 p. s. i. in the plywood sheathing, all of said stress therefore being less than the maximum.

As is set forth hereinabove, a roof of a house or other building may comprise a number of roof-understructure assemblies, each comprising a resilient bowed arch member, a chord member provided with thrust blocks, and plates for maintaining the ends of the bowed arch member, and sheathing of plywood or other

resilient sheet material co-extensively secured in common to a plurality of bowed arch members mutually laterally spaced from one another and in a substantial lateral alignment, whereby the attributes of high load-carrying and resilient resistance against wind, snow and like pressures are increased.

Whereas we have described our invention by reference to specific forms thereof, it will be understood that many changes and modifications may be made provided they do not depart from the scope of the claims.

We claim:

1. A roof structure comprising a tie beam; thrust blocks mutually spaced from one another and secured to said tie beam upon its upper face; an initially straight slender member bowed by application of forces at its opposite ends in opposing directions, the ends of said bowed member being lodged against said thrust blocks; plates secured to the upper faces of said thrust blocks for maintaining the ends of said member in position relative to said thrust blocks; resilient sheet material pre-stressed and secured co-extensively at its under face relative to the outer bowed face of said bowed member; and strut means supporting said bowed member.

2. A roof structure comprising a tie beam, thrust blocks mutually spaced from one another and secured to said tie beam upon its upper face; an initially straight slender member bowed by application of forces at its opposite ends in opposing directions, the ends of said bowed member being lodged against said thrust blocks; wedge means disposed between the inner faces of said thrust blocks and the respective ends of said bowed member; resilient sheet material pre-stressed and secured relatively to the convex face of said bowed member; and strut means supporting said bowed member.

3. A roof structure comprising a tie beam; thrust blocks mutually spaced from one another and secured to said tie beam upon its upper face; an initially straight slender member bowed by application of forces at its opposite ends in opposing directions, the ends of said bowed member being lodged against said thrust blocks; wedge means disposed between the inner faces of said thrust blocks and the respective ends of said bowed member; plates secured to the upper faces of said thrust blocks for maintaining the ends of said member in position relative to said thrust blocks; resilient sheet material pre-stressed and secured relatively to the convex face of said bowed member; and strut means supporting said bowed member.

4. A roof structure comprising a tie beam; thrust blocks mutually spaced from one another and secured to said tie beam upon its upper face; an initially straight slender member bowed by application of forces at its opposite ends in opposing directions, the ends of said bowed member being lodged against said thrust blocks; wedge means disposed between the inner faces of said thrust blocks and the respective ends of said bowed member; plates secured to the upper faces of said thrust blocks for maintaining the ends of said member in position relative to said thrust blocks; resilient sheet material pre-stressed and secured relatively to the convex face of said bowed member; strut means supporting said bowed member; and sheet roofing mate-

rial secured to the outer face of said sheet material.

5. A roof structure comprising a plurality of initially straight slender members, each bowed by application of forces at its opposite ends in opposing directions, said members being laterally spaced from one another and in substantial lateral alignment; tie beams individually associated with said members; thrust blocks secured to each tie beam, the ends of its associated bowed member being lodged relative to said thrust blocks; resilient sheet material pre-stressed and secured co-extensively in common to said plurality of bowed members; and strut means respectively supporting said bowed members.

6. A roof structure comprising a plurality of initially straight slender members, each bowed by application of forces at its opposite ends in opposing directions, said members being laterally spaced from one another and in substantial lateral alignment; tie beams individually associated with said members; thrust blocks secured to each tie beam, the ends of its associated bowed member being lodged relative to said thrust blocks; plates respectively secured to said thrust blocks for maintaining the ends of the associated bowed member in position relative to said thrust blocks; and resilient sheet material pre-stressed and secured co-extensively in common to said plurality of bowed members; and strut means respectively supporting said bowed members.

7. A roof structure comprising a plurality of initially straight slender members, each bowed by application of forces at its opposite ends in opposing direction, said members being laterally spaced from one another and in substantial lateral alignment; tie beams individually associated with said members; thrust blocks secured to each tie beam, the ends of its associated bowed member being lodged relative to said thrust blocks; wedge means associated with each bowed member and its thrust blocks for adjusting the bowed members in substantial mutual lateral alignment; resilient sheet material pre-stressed and secured co-extensively in common to said plurality of bowed members; and strut means respectively supporting said bowed members.

8. A roof structure comprising a plurality of initially straight slender members, each bowed by application of forces at its opposite ends in opposing directions, said members being laterally spaced from one another and in substantial lateral alignment; tie beams individually associated with said members; thrust blocks secured to each tie beam, the ends of its associated bowed member being lodged relative to said thrust blocks; wedge means associated with each bowed member and its thrust blocks for adjusting the bowed members in substantial mutual lateral alignment; plates respectively secured to said thrust blocks for maintaining the ends of the associated bowed member in position relative to said thrust blocks; resilient sheet material pre-stressed and secured co-extensive in common to said plurality of bowed members; and strut means respectively supporting said bowed members.
